UNITED STATES PATENT OFFICE.

JOHN N. RICHARDSON, OF CINCINNATI, OHIO, ASSIGNOR TO THE WILLIAMSON HEATER COMPANY, OF CINCINNATI, OHIO, A CORPORATION OF OHIO.

UNDERFEED MECHANISM.

1,314,903.

Specification of Letters Patent. Patented Sept. 2, 1919.

Application filed April 17, 1916. Serial No. 91,807.

To all whom it may concern:

Be it known that I, JOHN N. RICHARDSON, a citizen of the United States, and residing at Cincinnati, in the county of Hamilton and State of Ohio, have invented a new and useful Improvement in Underfeed Mechanism, of which the following specification is a full disclosure.

My invention relates to a fuel underfeed mechanism for furnaces, primarily intended for household heating and adapted to utilize pulverized coal or slack, and the principal object is to provide means holding the charger rigidly in a horizontal plane when lifting the fuel for charging.

In said invention the grate of the furnace is formed with a fuel charging port disposed in a horizontal plane so as to permit the fuel to be passed vertically and concentrically upward through the grate port into the lower portion of the combustion chamber, and the ash-pit is formed with a fuel receiving opening in a vertical plane, permitting the fuel to be shoveled into the upper end of the container.

There is a fuel container or cylinder movably mounted in the ash-pit, and means for bringing it into alternate registry with said port and opening, the cylinder being in vertical position for charging the fuel, and in position for gravity filling when alined with the ash-pit opening.

There is a fuel charger or piston in the container or cylinder, and means for raising it when the cylinder is alined with the grate port, and means for dropping the charger to the bottom of the container when the container is adjacent to the fuel receiving opening. The piston is preferably operated by a flexible or lever-type piston rod hinged to the under side of the piston, and means are disposed outside of the ash-pit for rocking the container and for operating the lever-type piston rod, preferably in step movements.

One of the objects of the invention is to compact the operative part of the mechanism which is within the ash-pit so as not to require an unduly large or vertically deep ash-pit.

Therefore, I have so constructed and arranged the interior operating mechanism that it lies and functions between the horizontal axis on which the cylinder is rocked

and the arc described by the upper end of the cylinder. This permits the cylinder to be pivoted in the ash-pit, slightly above or close to the floor line.

Also, an object of this invention is to combine the organized underfeed elements named with mechanical means for preventing the piston from tilting, that is to say, means for positively guiding the piston axially when the cylinder is in its alternate positions.

The piston and cylinder are designed to support and hold a rather heavy load of coal, say fifty pounds, which has to be lifted vertically through the cylinder and be forced through the grate port in opposition to the weight of the fuel in the combustion chamber. Necessarily this load of fuel cannot be evenly distributed over the piston area, and as the piston is moved through a lever hinged to the underside of the piston, it is desirable to provide means independent of the piston rod which will hold the piston positively and accurately at right angles to the axis of the cylinder throughout the piston movement and when the cylinder is in either one of its alternate positions. Therefore, preferably, this guide provision extends in a radial direction to the horizontal axis on which the cylinder is rocked.

In my underfeed, I employ an annulus grate providing a central opening constituting a fuel-charging port and enabling the rocking or oscillating of the annulus grate in relation to the centrally registering underfeed cylinder or its port-closing follower.

The general character of the mechanism is disclosed in a former joint application of myself and Edward A. Muller, Serial No. 846,486, filed June 22, 1914, and also in my former application, Serial No. 91,808, filed April 17, 1916, patented March 19, 1918, No. 1,260,056, the objects of the present improvement being above indicated and the differentiating mechanism being herein claimed.

These and other features of the invention will be more fully set forth in the description of the accompanying drawings forming a part of this specification, and disclosing the preferred embodiment of the invention, wherein:

Figure 1 is a section through the base of the furnace showing the fuel cylinder in charging position.

Fig. 2 is a similar view showing the cylinder in fuel receiving position, with the plunger and its operating rack at the limit of fuel charging position ready to be released to lower the plunger.

Fig. 3 is a detailed view of the rack and pawl mechanism in released position.

Fig. 4 is a top plan view of the cylinder.

Fig. 5 is a sectional view similar to Fig. 2, 10 showing the plunger in its lower position.

Fig. 6 is a similar sectional view showing the cylinder in charging position and the plunger in elevated position.

The fuel cylinder or container 1 is pivotally mounted within the ash-pit, and when in vertical charging position, as shown in Fig. 1, registers with a charging port 2 in the grate 3. A charging plunger or fuel elevator 4 slides in the cylinder, its upper 15 surface and the upper surface of a shield 5, which extends rearwardly from the top of the cylinder, form, when the plunger is in its upper position, a continuous surface concentric to the pivotal bearing of the cylinder; also, said surfaces are convexed transversely on a smaller radius to prevent side 20 play of the cylinder.

Upon the inner wall of the ash-pit and upon opposite sides thereof are secured the 30 brackets 50 having pivots 51, upon which the cylinder is rocked, this horizontal axis being preferably positioned just slightly above the floor line. The fuel container or cylinder 1 is formed with extensions 52 projecting radially downward from opposite sides of the bottom of the cylinder, in the lower ends of which the pivots 51 have bearings, thus enabling the cylinder to rock into alternate registry with the grate port and 35 the fuel receiving opening.

The cylinder is limited in its rearward swing by a lug 6, upon which the rear end of the shield 5 rests when the cylinder is in charging position. To the web 7 of the cylinder is pivoted an arm 8, which is connected to the plunger 4, by a link 9, said pivot extending through the web 7 and having secured thereto an arm 10, to which is pivotally connected the toothed charging or 45 ratchet bar 11. To the side of the cylinder is pivotally connected the tilting link 12, which extends exteriorly of the ash-pit and is pivotally connected to a rocker element or tilting plate 13. Said plate is pivoted at 14, 50 on a base extension 15, and is provided with a handle socket 16, receiving the tilting handle 17. 18 represents a fulcrum pin which is secured in the tilting plate and projects through an elongated slot 19 in the toothed 55 ratchet bar 11, thereby serving as a support and guide for the outer end thereof.

Loosely pivoted on the fulcrum pin 18, between the tilting plate and the ratchet bar is an oscillatory actuator member or pawl 60 carrying plate 20, which is provided with a

socket 21, receiving a charging handle 22. Pivoted on this plate above and below the ratchet bar are a pair of actuating pawls or ratchet elements 23, 24, which engage the upper and lower toothed edges 25, 26, of said 70 bar. The pawl 23 is a gravity pawl and the pawl 24 is provided with a pin 27, which projects through a slot 28 formed in the forward arm of a release lever 29. Said release lever is pivoted on the pin 18 and has a 75 weighted arm 30 extending to the rear of its pivotal point.

This construction, in fact, makes the pawl 24 also a gravity pawl through a second element, (the weighted release lever). The 80 pawl 23 has a downwardly projecting arm 31, carrying a pin 32, which is in the path of movement of shoulder 33 of the release lever 29. The release lever has a foot-plate 34 at its forward end and by an examination of 85 Fig. 3, it will be seen that a downward pressure on the foot-plate 34 will rock the release lever 29 and disengage both pawls from their respective toothed edges 25, 26, of the charging bar 11. Such disengagement will 90 permit the charger 4 to drop by gravity until the rear edge of the arm 8 strikes a ledge 35 on the web 7. To prevent the charger from dropping too rapidly, a retarding device has been incorporated in connection 95 with the release lever and consists in a brake arm 36, which is secured to the forward arm 30 of the release lever and has an in-turned lower end projecting beneath the ratchet bar. The lower edge of the ratchet 100 bar adjacent to the teeth is undulated and when the release lever is rocked, (see Fig. 3), the inturned end of the brake arm 36 engages these undulations, with the effect of retarding the lateral movement of the 105 ratchet bar.

In the position shown in Fig. 1, the release lever is inoperative to trip the pawls, because as soon as it is rocked slightly, its forward end will contact with the floor- 110 plate 38. This would partly withdraw the pawl 24, but such movement is not sufficient to bring the shoulder 33 of the release lever into contact with the pin 32 of the pawl 23 to rock said pawl unless there is sufficient free 115 play in the parts to permit the charging handle 22 to rock backward beyond its normal position, as shown in Fig. 1, so that the normal distance between the shoulder 33 and pin 32 would be lessened. To guard against 120 this possible condition, I provide a latch lever 40, which is loosely pivoted on the base plate extension 15, at 41, and is limited in its downward movement by a pin 42, engaging the rearwardly projecting arm thereof. The forward hooked end engages over a pin 43 on the pawl carrying plate 20 and retains it in its normal position. When the tilting plate 13 is rocked, the pin 43 rises into a notch 44 in the latch plate 40, which pre- 125

vents the charging handle dropping forward when the pawls are tripped.

The cycle of operation is as follows:

Referring to Fig. 1, it will be assumed that the cylinder is full of fuel and it is desired to charge the furnace. The charging handle 22 is rocked backward and forward to transmit a step by step movement to the ratchet or charging bar 11, through the pawl and tooth mechanism. After the 10 charger is fully elevated, the cylinder is tilted forward to fuel receiving position, (see Fig. 2), by rocking the tilting plate 13, by means of the handle 17. The release lever 29 is now rocked, (see Fig. 3), to disengage the pawls and to allow the plunger to drop under control of the retarding brake arm 36, the effectiveness of which depends upon the pressure applied to the foot-plate 34. The cylinder is now refilled with fresh 20 fuel and the tilting lever 17 is rocked forward to swing the cylinder to charging position, etc. The tilting plate 13 is limited in its forward rocking movement by a lug 25 45 which contacts with the base plate extension 15.

The inner surface of the cylinder 1 and its extensions 52 are formed with the key seats or guides 53 extending parallel with the axis of the cylinder, and also radially with relation to the horizontal axis on which the cylinder rocks. The piston 4 is relatively thin, and its periphery is formed with the downwardly extending flanges 54, 30 formed with the keys 55 extended below the piston and fitting into the key seats 53. This key seat arrangement preferably extends radially to the arc of cylinder swing, and holds the piston rigidly and accurately 35 at right angles to the axis of the cylinder throughout the piston movement when the cylinder is moved to either of its alternate positions. Also, this axially extended key-seat provision enables the use of a relatively thin piston, which is desirable when 40 slack or pulverized coal is to be used, as a piston thick enough to prevent tilting would involve too great dimensions of bearing surfaces, and fine fuel working in between the 45 peripheral portions of the piston and cylinder would cause binding.

In this invention, preferably, the piston-flange keys extend down to or beyond the point where the piston rod or lever is pivotally connected to the under side of the piston and so effectually prevent the piston from tilting in the cylinder. Also, the extension of the key ways onto the radial legs 11 enables the piston to be moved to the extreme 50 lower end of the cylinder. These key seats and keys extend radially from the horizontal axis on which the cylinder swings, so that the piston is held rigidly at right angles to this radius in either position of the cylinder. Preferably, the upper face of the

piston has a spherical contour to coincide with the contour of the apron 5 when the piston is at the upper end of its movement.

The mechanisms are compact, easily operated by nonskilled attendants, and the mechanisms operate on principles effectually preventing the malfunctioning of the parts. At the same time this mechanism may be readily applied to a furnace of ordinary dimensions without taking up too much room in the cellar, and the mechanism can be easily connected up with the furnace.

The principles of the invention are susceptible of wide varieties in the light of this disclosure.

It is most important to construct and mount the grate in relation to the underfeed in a manner permitting said grate to be oscillated about its vertical axis while either the piston in its uppermost position 85 or the follower is in registry with the central grate opening, enabling the ashes to be shaken out, the central portion of the fuel bed being supported stationary by the underfeed elements, while the marginal fuel body is supported by the oscillating grate 90 and can be moved around this fixed center, thus torsionally breaking up the fuel bed most advantageously thereby freeing the ash. This is effected by providing the grate 95 with an annular rib 56 resting on a vertical roller 57 pivotally mounted in a bracket 59, the grate being guided by a horizontal roller 58 also pivotally mounted in the bracket 59 and bearing against the inner side of the 100 rib 56 of the grate. There are several pairs of these rollers distributed around the margin of the grate, but in the drawings only one pair is shown.

Certain phases and features of the mechanism herein disclosed but not claimed are made the subject-matter of a separate application filed of even date herewith, Serial No. 91,808.

Having thus described my invention, I 110 claim:

1. A fuel underfeed for furnaces comprising a circumferential grate providing a central fuel port, a cylinder and port closer in the ash pit movable into and out of registry with said port, a piston having a key slide engagement within the cylinder, means for moving the cylinder, and independent means for moving the piston.

2. A fuel underfeed for furnaces comprising a circumferential grate movable on its axis and providing a central fuel port, a cylinder and port closer in the ash pit movable into and out of registry with said port, a piston having a key slide engagement within the cylinder, a rod hinged to the piston, means for moving the cylinder, and independent means for operating said hinged piston rod.

3. A fuel underfeed for furnaces com-

prising a circumferential grate movable on its axis and providing a central fuel port, a cylinder and port closer in the ash pit movable into and out of registry with said port, a piston formed with a thin peripheral edge in said cylinder, the piston and cylinder being formed with a key slide engagement, a rod hinged to said piston, means for moving the cylinder, and independent means for moving the piston.

4. A fuel underfeed for furnaces comprising a circumferential grate providing a central fuel port, a cylinder and port closer in the ash pit movable into and out of registry with said port, a thin peripheral edged piston in the cylinder having flanges formed with a key slide engagement within the cylinder, a rod hinged to the piston, means for moving the cylinder, and independent means for operating the hinged piston rod.

5. A fuel underfeed for furnaces comprising an annular grate having a fuel port, a cylinder and port closer in the ash pit movable into and out of registry with said port, a piston having a key slide engagement within the cylinder, means for moving the cylinder, means for independently raising the piston in a series of short, definite steps for positively supporting the piston at the end of each step, and means for returning the piston in a single movement when the cylinder is out of registry with the fuel port. 25

In witness whereof, I hereunto subscribe my name, as attested by the two subscribing 30 witnesses.

JOHN N. RICHARDSON.
